TRAY OR SIMILAR ARTICLE

Stanford Pavenick, South Orange, N.J.
(% Aljen Mfg. Corp., 113 Grand St., New York, N.Y.)

Filed Dec. 4, 1958, Ser. No. 53,648

Term of patent 7 years

(Cl. D44—10)

Fig. 1 is a top plan view of a tray, showing my new design;

Figs. 2 and 3 are side and end elevational views respectively of said tray; and

Fig. 4 is an enlarged sectional view taken substantially along the line 4—4 of Fig. 1.

I claim:

The ornamental design for a tray or similar article, substantially as shown.
